UNITED STATES PATENT OFFICE.

JAMES S. PATTEN, OF BALTIMORE, MARYLAND.

DESIGN FOR A DUST-GUARD SECTION.

SPECIFICATION forming part of Design No. 29,769, dated December 6, 1898.

Application filed November 12, 1898. Serial No. 696,313. Term of patent 14 years.

To all whom it may concern:

Be it known that I, JAMES S. PATTEN, a citizen of the United States, residing at Baltimore, in the State of Maryland, have invented and produced a new and original Design for Dust-Guard Sections, of which the following is a specification, reference being had to the accompanying drawings, forming part thereof, in which—

Figure 1 is a perspective view, and Fig. 2 is a face view, of a dust-guard section, showing my new design.

As shown in the drawings, the leading or material feature of my design consists of a plate having the side arms A, with the curved surface B at the base of said arms and the sloped ribs C at the inner edges of the said

arms. Minor features are the grooves D, extending from side to side of the upper ends of said arms, and the perforations E in said arms and intersecting the grooves D, as will be understood from the drawings.

The curved surface B is shown as extended at B' and forming curved ends at the lower extremities of the ribs C.

Having described my invention, what I claim as new, and desire to secure by Letters Patent, is—

The design for a dust-guard section, as herein shown and described.

JAMES S. PATTEN.
